TWO-TEMPERATURE REFRIGERATOR

Lawrence A. Philipp, Detroit, Mich., assignor to
 Nash-Kelvinator Corporation, Detroit, Mich.,
 a corporation of Maryland

Application October 19, 1951, Serial No. 252,145

4 Claims. (Cl. 62—103)

1

This invention relates generally to refrigerating apparatus and more particularly to such apparatus in which multiple temperatures are maintained.

One of the objects of my invention is to provide in a refrigerator having a freezing compartment and a food storage compartment, an improved arrangement and relationship of cabinet walls and a compartment separating partition-damper unit, to control the circulation of air between the compartments and thus regulate the humidity of the food storage compartment.

Another object of the invention is to provide an improved refrigerator in which freezing and food storage compartments are separated by a removable partition having a rear edge spaced from the cabinet rear wall to provide an air passage and having a damper hinged to the rear edge of the partition to control the air passage.

Another object of the invention is to provide an improved combined air baffle and damper for use in separating freezing and food storage compartments and for controlling the circulation of air therebetween.

Another object of the invention is to provide an improved combined drip pan and air circulating control damper in which the damper is hinged to the pan externally thereof and has a raised or closed position in an air flow space between an edge of the pan and a wall of the cabinet to decrease air flow, and has a lowered or open position externally of the pan to increase air flow.

Another object of the invention is to provide in a refrigerator, an improved combined drip-pan and air-circulating control damper in which the damper is pivoted to and within the pan to lie therein in open position and movable to a closed position outside the pan to decrease air flow between the wall of the refrigerator and an adjacent edge of the pan.

Further objects and advantages of the present invention will be apparent from the following description, reference being had to the accompanying drawings, wherein a preferred form of the present invention is clearly shown.

In the drawings:

Fig. 1 is a front view partly broken away of a refrigerator embodying features of my invention;

Fig. 2 is a side view of the refrigerator partly broken away and in section to show units of the refrigerating system;

Fig. 3 is a horizontal sectional view of the re-

2

frigerator, taken along line 3—3 of Fig. 1 showing my improved air baffle-damper unit in plan;

Fig. 4 is a vertical sectional view of the air baffle-damper unit, taken along the line 4—4 of Fig. 3;

Fig. 5 is an enlarged fragmentary elevational view of the air baffle-damper unit, taken in the direction of the arrows 5—5 of Fig. 4;

Fig. 6 is a sectional view of the air baffle-damper unit, taken along line 6—6 of Fig. 5;

Fig. 7 is a horizontal sectional view of the air baffle-damper unit, taken along line 7—7 of Fig. 6;

Fig. 8 is a vertical sectional view of the air baffle-damper unit, taken along line 8—8 of Fig. 5;

Fig. 9 is a view similar to Fig. 6 showing the damper in open position;

Fig. 10 is a sectional view similar to Fig. 4 of a modification of the air baffle-damper unit, showing the damper in open position;

Fig. 11 is an enlarged fragmentary plan view of the modified air baffle-damper unit, showing the damper in open position;

Fig. 12 is a detail sectional view of the air baffle-damper unit, taken along line 12—12 of Fig. 11; and

Fig. 13 is a sectional view of the air baffle-damper unit, showing the damper in closed position.

Referring to the drawings by characters of reference, there is shown a refrigerating apparatus of the household type having a cabinet 20, and a refrigerating system including a refrigerant evaporator 22, a refrigerant condensing element 24, and a motor-compressor unit 26. The evaporator 22 is located within the cabinet 20 adjacent the top thereof; the condensing element 24 is located at the back of the cabinet; and the motor-compressor unit 26 is housed within a machinery compartment 28 of the cabinet, adjacent the bottom thereof. Refrigerant supply and return conduits 30 and 32 connect the evaporator 22 and condensing element 24 together. Preferably, the supply conduit 30 is a

small diameter or capillary tube adapted to supply liquid refrigerant from the condensing element 24 in proper amounts to the evaporator 22 to maintain desired refrigeration thereof.

The present cabinet construction comprises, in general, a metal casing 34 and a metal liner 36 separated by suitable heat insulating material 38. The casing 34 and liner 36 are box-shaped having adjacent spaced edges spanned preferably by heat breaker strips 40 which extend

along the sides, top and bottom of the cabinet at the front thereof giving also a finished appearance to the cabinet. A door access opening at the front of the cabinet is closed by a door 42 which is hinged to one of the cabinet side walls, as at 44.

The evaporator 22 may comprise a refrigerant coil or conduit 46 and an extended heat absorbing member in the form of a metal box-like container 48. As shown, the evaporator coil 46 is wound about the container 48 in a manner to extend along and in contact with the top, bottom and sides thereof. Suitable clamps, cement or other means may be used to secure the coil 46 to the walls of container 48 to insure efficient heat transfer by conduction therebetween.

Any suitable type of condensing element may be used in the refrigerator, such as the sealed type motor-compressor unit 26 and a condenser coil 52. In the usual manner, liquid refrigerant from the condenser 52 is delivered by the capillary tube 30 to the evaporator 22 where evaporation takes place, the resultant gaseous refrigerant being returned to the condenser 52 by the return conduit 32 and motor-compressor unit 26.

Preferably, the evaporator 22 extends across the cabinet substantially to the side walls thereof, and also extends substantially from the door 42 to the rear wall of the cabinet with suitable space provided between the evaporator top and front surfaces and the liner surfaces to allow for circulation of air around the evaporator 22. In addition to functioning as an extended heat absorbing member of the evaporator coil 46, the container 48 forms a chamber wherein ice may be made in suitable trays (not shown) and wherein foods may be frozen. Also, the capacity of evaporator coil 46 is made such that the evaporator 22 will refrigerate, by air convection, foods to be stored below the evaporator 22 or in a food storage compartment 50 formed in part by the inner wall surfaces of liner 36. If desired the food storage compartment 50 may be additionally cooled by a secondary refrigerating system as disclosed and described in my Patent Number 2,361,792 issued October 31, 1944.

Disposed below and adjacent the underside of evaporator 22, I provide a horizontal partition or air baffle, designated generally by the numeral 54 which separates the evaporator 22 from and forms the top wall of the food storage compartment 50. The air baffle 54 extends substantially to the liner sides, but is spaced from door 42, as at 58, and from the liner rear wall, as at 60, to provide air passages for circulation of air between the food storage compartment 50 and evaporator 22 to obtain cooling of the former by convection. Relatively cold air descends from the freezing compartment at the back of evaporator 22 through passage 60 into the food storage compartment 50 and relatively warm air flows up the front of the cabinet near the inner side of the door 42 about the evaporator 22 and moisture in the air is deposited as frost on the evaporator 22 so that continued circulation tends to dehumidify the air.

The air baffle 54 comprises, in general, a pan structure 64 and a damper 66. The damper 66 is pivotally attached to the rear edge of pan 64 and is manually operable to control the flow of air through passage 60 so that the rate of air circulation between the food storage compartment 50 and the evaporator 22 may be regulated to in turn regulate the humidity in the food storage compartment.

Suitable slideways or rails 68 are secured to the sides of the liner 36 to support the air baffle 54 which is removable by sliding it forwardly on slideways 68 out of the cabinet doorway. Rearwardly facing abutments 70 on the baffle sides are arranged to abut the front ends of the slideways 68 as a stop to limit the extent to which the baffle 54 may be slid into the cabinet and thus determine the minimum width of the air passage 60.

The pan 64 is generally rectangular in shape as seen in plan (Fig. 3) and in the present construction, the pan is made in two sections comprising, an upper pan member 72 and a bottom pan member 74. Also in the present construction, the pan members 72, 74 are made of plastic material and between them is preferably provided suitable heat insulation 76 to decrease heat transfer between the food storage compartment 50 and the evaporator 22. The pan sections 72, 74 may be secured together by any suitable cement or by any other suitable means. Pan 64 also serves as a drip receiver during defrosting operation of the evaporator 22 and the upper pan member 72 is preferably provided with upstanding water retainer and reinforcing front, side and rear flanges 78, 80 and 82 respectively. Also, the upper pan member 72 is preferably inclined from the front thereof downwardly to its rear flange 82 to drain water to a drain outlet 84 from which the water may drain into a removable and smaller container 86 that is preferably supported on the top shelf 88 of the food storage compartment 50. A defrost water drain trough 87 is mounted on the liner rear wall to receive water which runs down the liner during the defrosting period. This trough 87 is spaced directly above the damper 66 to prevent water from dripping into the food storage compartment and has a spout 89 overhanging pan 64 to discharge the defrost water thereinto, preferably at the pan drain outlet 84.

The damper 66 extends along the rear edge of pan 64 substantially co-extensive therewith and is attached to the pan by hinges 90 of which there are three in the present construction. As shown in Fig. 9, the damper 66 has an open position in which it is in a vertical position against the pan rear flange 82 and as shown in Fig. 4 has a closed or raised position in which the damper extends into air circulating passage 60 to decrease the flow capacity thereof. In raised damper position, the rear edge of the damper 66 is slightly spaced, as at 92, from the rear wall of liner 36 to allow a minimum of air circulation between food storage compartment 50 and evaporator 22.

Hinges 90 each comprise a hinge member 94 on pan 64 and hinge pintles 96 formed integral with damper 66 at the rear edge thereof. The hinge member 94 is formed integral with the pan rear flange 82 and includes a supporting or bearing wall portion 98 to receive the pintles 96, the wall portion 98 being slightly inclined upwardly and rearwardly and having a rear upstanding end or flange 99. Also formed integral with the pan rear flange 82 and with wall portion 98 is an upright boss 100 midway between the end edges of portion 98 to reinforce the same and to provide support for a retainer plate 102 which seats flat on the top of the boss 100 and on edges of flanges 82 and 99 to provide pintle retainers 103. The plate 102 is secured to the boss 100 by a screw 104. It will be seen that the pintle retainers 103 are elongated from the pan rear flange 82 rearwardly to allow the damper 66 to be moved bodily toward

and away from the pan 64, as well as to allow the damper to pivot.

The damper 66 has a clearance opening 106 of general rectangular shape at its hinged edge for clearance with the pan hinge member 94 and extending from opposite side edges of opening 106 toward each other, the pintles 96 have their ends, as at 97, spaced apart for clearance with the boss 100. On the hinge member flange 99, upwardly facing seats 108 are provided at opposite side edges of the flange to receive abutments 110 on the damper 66. The abutments 110 are formed integral and coplanar with the damper 66 and are positioned to rest on seats 108 to hold the damper in raised position, as shown for example in Fig. 6. At their front edges, the abutments 110 have downwardly directed edges 112 to hook behind the upstanding edges of flange 99 adjacent seats 108 to retain the damper 66 on the seats. In this position of damper 66 it will be noted that the pintles 96 engage against the underside of the retainer plate 64, as shown in Fig. 6, to aid in holding the damper on the seats 108.

To change the position of the damper 66, assuming for example that the humidity in the food storage compartment is higher than desired, the baffle unit is withdrawn from the cabinet and the damper 66 is lowered by first raising it slightly until the hooked end abutments 112 clear seats 108 and by then moving the damper bodily rearwardly until the abutments clear the seats 108 after which the damper may be swung down flat against the pan rear flange 82, as shown in Fig. 9. With the passage 60 now open, increased rate of air circulation will be had between the food storage compartment 50 and the evaporator 22 during which additional moisture will be frozen out of the circulating air on the evaporator and consequently lower the humidity of the food storage compartment 50.

Referring now to the modification shown by Figs. 10 to 13 inclusive, this construction is similar to the preferred form and therefore like parts have been designated by like reference numerals to avoid unnecessary repetitious description. In the modification, the baffle or pan, designated generally by numeral 114 has a rear upstanding flange 116 integral with which are a number of bosses 118 of which only one is shown. These bosses 118 are spaced horizontally along the pan rear flange 116 and extend inwardly therefrom. Each of the bosses 118 is provided with a groove or bearing 120 in its upper end and these bearings are in alignment to receive respectively aligned pintles 122 on a damper 124. The pintles 122 are preferably formed integral with the damper 124 near one longitudinal edge thereof and are retained in the bearings 120 by retainer plates 126 which are secured to the upper ends of bosses 118 by screws 128. In open position of the damper 124 as illustrated in Fig. 10, the damper lies within and flat on the bottom of the pan, whereas in closed position, the damper rests on the upper edge of pan rear flange 116 which holds the damper in closed position in passage 60, as shown in Fig. 13, decreasing the rate of air flow through said passage.

Although preferred and modified forms have been illustrated, and described in detail, it will be apparent to those skilled in the art that various other modifications may be made therein without departing from the spirit of the invention or from the scope of the appended claims.

I claim:

1. In a refrigerator, a cabinet having vertical

walls, a horizontal drip pan within said cabinet cooperating with said walls to form an upper freezing compartment and a lower food storage compartment, said drip pan having opposite edges respectively spaced from adjacent opposite walls of said cabinet to allow for circulation of air between said freezing and food storage compartments, a damper hinged to said drip pan and movable to a raised position extending from one of said edges toward the adjacent cabinet wall to decrease air circulation, and a drip trough extending along said adjacent cabinet wall overlying said damper and discharging into said drip pan.

2. In refrigerating apparatus having a cabinet, a partition for separating a freezing compartment and a food storage compartment within the cabinet comprising, a pan, an external boss on said pan, an upwardly facing seat on said boss spaced from said pan, a damper pivoted to said boss having raised and lowered positions, the pivoted connection between said boss and damper being loose to allow said damper to be moved bodily toward and away from said pan, and a seating portion on said damper to rest on said seat to hold said damper in raised position and engageable with said seat when said damper is moved toward said pan.

3. In refrigerating apparatus having a cabinet, a partition for separating a freezing compartment and a food storage compartment from each other, comprising, a pan, an external boss extending from one edge of said pan having an upwardly directed portion spaced from said pan edge, a damper extension of said pan edge movable to a raised position or to a lowered position, a pintle on said damper loosely engaging between said pan edge and said upwardly directed portion to allow said damper to be moved bodily toward and away from said pan edge, a seat on said upwardly directed portion, and a seating portion on said damper to engage said seat when said damper is in raised position and toward said pan edge.

4. In a refrigerator, a cabinet having side and rear walls, a horizontal pan within said cabinet separating freezing and food storage compartments from each other, said pan having opposite edges thereof spaced respectively from opposite walls of the cabinet to effect air circulation between said freezing and food storage compartments, a boss within said pan adjacent one of said edges, a damper hinged to said boss having an open position seating on and within said pan and having a position projecting into one of said spaces toward the adjacent cabinet wall to decrease air circulation, a seat on the upper edge of said pan adjacent said boss to receive and hold said damper in said last-named position and inclined downwardly to said pan to drain drip water thereinto, said damper having an edge spaced from said adjacent cabinet wall to effect restricted air flow, and a drip deflector on said adjacent cabinet wall overlying said damper and directing flow into said pan.

LAWRENCE A. PHILIPP.
